Fig. 2

FIG. 1 is an elevational view of a bottle embodying my new design;

FIG. 2 is a bottom plan view thereof;

FIG. 3 is a top plan view thereof with the broken line elements seen at the top of FIG. 1 being omitted for convenience of illustration;

FIG. 4 is a fragmentary sectional view taken in the direction of the arrows on the horizontal section plane passed through the line 4—4 of FIG. 1;

FIG. 5 is a fragmentary sectional view taken in the direction of the arrows on the vertical section plane passed through the line 5—5 of FIG. 1.

The dominant features of my design reside in the portions shown in full lines.

I claim:

The ornamental design for a bottle or similar article, as shown and described.
